UNITED STATES PATENT OFFICE.

HERBERT E. IVES, OF MONTCLAIR, NEW JERSEY, ASSIGNOR TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed May 6, 1924. Serial No. 711,338.

This invention relates to means for transmitting pictures by electricity and more particularly to an arrangement for operating the scanning mechanism.

5 In systems heretofore known employing revolving drums for helical scanning, some mechanism has always been provided to return the drum to a given position after the transmission of each picture and before 10 starting the transmission of another picture. Various devices have been employed. All have had their characteristic defects. Some were too complicated or delicate to be practicable. Others required too much operating time. All were therefore expensive and 15 uneconomical.

An object of the present invention is to economize operating time in such a system without sacrificing simplicity and reliability.

20 In one embodiment of the present invention, the equipment of a picture transmission system employing transmitting and reproducing drums is so arranged that a picture may be transmitted while the drums are 25 moving in either direction. The drums are driven by reversible La Cour motors. As the drums rotate they also move axially with respect to the optical portions of the system. The entire picture surface is thus 30 traversed while the drums move axially from one end to the other in either direction. Each motor is coupled to its respective drum through a friction drive, the movement of the drum being controlled by 35 a magnetically operated detent which prevents rotation in either direction. The motors are synchronized over one voice frequency carrier current channel while the picture characteristics are transmitted as 40 modulations of another voice frequency carrier current channel of different frequency.

The novel features which are considered characteristic of this invention are set forth with particularity in the appended claims. 45 The invention, both as to its organization and method of operation together with other objects and advantages thereof, will be further explained in the following description having reference to the accompanying drawings consisting of the following figures:

Fig. 1 is a schematic circuit arrangement of the transmitting terminal equipment.

Fig. 2 is a schematic circuit arrangement of the reproducing terminal equipment.

Fig. 3 shows the mechanical arrangement 55 of the magnetic detent.

Fig. 4 is a cross sectional view of the arrangement of Fig. 3.

The general arrangement of the system is similar to that shown in a copending application of M. B. Long, Serial No. 681,347, filed December 18, 1923 and reference may be had thereto for a more detailed description of the system than is given hereinafter.

The same reference characters are used in 65 the several figures to designate the same elements.

The terminal equipments of Figs. 1 and 2 are each shown connected to a line L. The complete system is accordingly shown by 70 connecting line L of Fig. 1 to line L of Fig. 2 through any circuit suitable for transmitting ordinary telephone currents such, for example, as an ordinary telephone line, a carrier current telephone channel or a radio 75 telephone channel.

Referring now to Fig. 1, a sending drum 5 is driven by a phonic wheel or La Cour motor 6 by means of a shaft shown diagrammatically by dotted lines. The coupling between drum 5 and the phonic wheel 6 is through a friction clutch 7. The phonic wheel 6 is itself driven by tuning fork SF in well known manner. An oscillator-amplifier SO-A supplies carrier waves to the 85 line L through a circuit 8 and low-pass filter SSF. A contact 9 on the tuning fork SF short-circuits circuit 8 periodically at the frequency of vibration of the tuning fork SF. At the reproducing terminal of Fig. 2, 90 these synchronizing waves are transmitted through low-pass filter RSF to an amplifier-detector RSA-D, detected current from which drives the reproducing tuning fork RF by means of a driving magnet 10. The 95 receiving fork RF drives phonic wheel 11 in well known manner which in turn drives reproducing drum 12 through friction clutch 13 and shaft 14. The shaft is shown diagrammatically by dotted lines.

At the transmitting terminal of Fig. 1, the photo-electric cell 15 inside of sending drum 5 is connected to the input circuit of picture current amplifier PCA. Light from a lamp 17 is focused by means of lens 18 upon the 105 surface of the sending drum 5 which is transparent. On the surface of drum 5, a transparency of the picture to be transmitted is

secured and light from the source 17 passing through this transparency of the picture into the photo-electric cell 15 causes a varying current to flow through the photo-electric cell 15 and to be impressed upon the input circuit of picture current amplifier PCA. The output circuit of the picture current amplifier PCA is connected to the input circuit of the modulator PM. An oscillator PO supplies the carrier waves for the transmission of the picture characteristics. These waves are amplified in an amplifier MCA and then transmitted to the line L through a high-pass filter SPF.

15 Waves from the oscillator PO may be impressed upon the amplifier MCA by either one of two paths. One path extends from the oscillator PO through shielded transformer 21, potentiometer 22, when switch 23 is closed, circuit 24, modulator PM, output circuit 25 which includes the contact 26 of relay 27 and potentiometer 28 to amplifier MCA. The other path extends from the transformer 21, through contact 29 of relay 27, and potentiometer 28 to amplifier MCA.

20 The energizing circuit for the upper winding of relay 27 includes battery 46, switch 47 and relay 48. If this energizing circuit is opened at switch 47, the lower winding of relay 27 is effective to close contact 26. When switch 47 is closed (as shown) the upper winding of relay 27 is effective to close contact 29. Under this same condition, armature 49 of relay 48 is attracted and locks the sending drum 5 against rotation in either direction.

25 At the reproducing terminal of Fig. 2, picture carrier waves from the oscillator PO are transmitted by high-pass filter RPF, amplified by amplifier RPA and impressed upon reproducing demodulator RPD. Connected in the output circuit of demodulator RPD is a battery 30, movable string 31 of light valve V and winding 32 of relay 33. The movement of the string 31 of light valve V controls the amount of light from lamp 43 which may affect a sensitive light recording blank or film secured to the reproducing drum 12. The light from the lamp 43 is directed first upon the movable spring 31 of light valve V. An image of the opening formed by the string 31 is then focused upon the surface of the drum by the lens as shown.

30 The armature of relay 33 is held in the position shown with contact 34 closed by the current flowing in the winding 32 when carrier waves are impressed upon the input circuit of demodulator RPD. When such waves are not being received, the armature of relay 33 is moved into a position closing contact 35 by current in winding 36 from battery 37.

35 The closure of switch 38 completes a circuit for relay 39 through battery 40. The

current in relay 39 attracts its armature 41 to lock drum 12 and prevent its rotation in either direction. Another circuit for relay 39 through battery 40 is closed when contact 34 of relay 33 is closed even though the 7 switch 38 is opened. It is to be noted that the closure of switch 38 forms a short circuit about the contact 34. A circuit which is completed by the closure of which 42 and contact 35, forms a short-circuit about the 75 winding 32 of relay 33.

The well known three-electrode electron discharge devices are preferably used throughout the system for the oscillators, modulators, demodulators and amplifiers. 80 The filters are designed according to the principles set forth in Campbell Patent No. 1,227,113, May 22, 1917.

85 The detent mechanism will now be described with reference to Figs. 3 and 4. The same mechanism may be used at both the transmitting and reproducing terminals. It will therefore be described by using only the reference characters of the transmitting terminal of Fig. 1. The magnet 39, armature 41 and drum 12 of Fig. 2 correspond respectively, to the magnet 48, armature 49 and drum 5 of Fig. 1.

90 The drum 5 and the detent mechanism including magnet 48 and armature 49 are mounted on a carriage 50 which may slide back and forth along guides 51 mounted on a frame 52. The threaded shaft 53 is geared to shaft 54 so that their speeds of rotation bear a definite relation to each other. Preferably, this speed ratio is unity. The threaded shaft 53 engages with screw collar 55 attached to the frame 50 so that the rotation of shaft 53 causes the movement of frame 50 along the guides 51. Mounted on the 105 shaft 54 in fixed relation thereto is a collar 56 which has a square notch 57 cut in its periphery. The notch 57 is just large enough to receive one end of the armature 49 which drops into the notch when the magnet 48 is 110 energized and so prevents rotation of the drum 5 in either direction. When drum 5 is held stationary, shaft 53 is prevented from rotating and movement of the frame 50 with respect to the guides 51 is prevented. The 115 armature 49 is normally held out of engagement with the collar 56 by a spring 58.

Method of operation.

120 The method of operation will now be described.

Drums 5 and 12 are set at one end or the other of their axial travel. A transparency of the picture is placed on drum 5 and a sensitive record blank is secured to drum 12. 125 Switch 47 is closed which locks drum 5 through the energization of relay 48 and closes contact 29 of relay 27. Switch 38 is closed which locks drum 12 by the energization of relay 39. Switch 42 is kept open. 130

The transmission apparatus, such as the oscillators, amplifiers, etc., are then energized. Synchronizing carrier waves from the oscillator-amplifier SO-A are transmitted through circuit 8, low-pass filter SSF, line L, low pass filter RSF to amplifier-detector RSA-D. Picture carrier waves are supplied by oscillator PO and transmitted through transformer 21, contact 29 of relay 27, amplifier MCA, high-pass filter SPF, line L, high-pass filter RPF, amplifier RPA to demodulator RPD. Demodulated current flows in string 31 of light valve V and winding 32 of relay 33 to close contact 34.

15 Tuning fork SF is then set in vibration and phonic wheel 6 is started in such a direction as to tend to move drum 5 toward its opposite end. The rotation of phonic wheel 6 tends to rotate sending drum 5 through friction clutch 7 but drum 5 is locked by armature 49 of relay 48. At contact 9 of fork SF, the train of carrier waves from oscillator-amplifier SO-A is periodically interrupted at circuit 8, so that trains of waves 20 are transmitted to the line L. These waves in amplifier-detector RSA-D cause impulses of current in driving magnet 10 to drive tuning fork RF in synchronism with tuning fork SF. Phonic wheel 11 is started in a direction tending to move cylinder 12 to its opposite end. The rotation of phonic wheel 11 tends to drive drum 12 through friction clutch 13 but is prevented from doing so by armature 41 of relay 39.

25 Switch 23 is now closed and switch 38 is opened. Picture carrier waves from oscillator PO are impressed upon the input circuit of modulator PM, the output circuit of which is open, however, at contact 26 of relay 27. Drum 12 is held in locked position by the energization of relay 39 through a circuit including contact 34. Everything is now in readiness to start the transmission of the picture. Phonic wheels 6 and 30 45 11 are rotating synchronously. Drums 5 and 12 are locked against rotation. Light valve V is energized by demodulated picture carrier waves.

To start the actual transmission, switch 47 is opened and left open during the transmission process. The opening of switch 47 de-energizes relay 48 which unlocks sending drum 5. The upper winding of relay 27 is simultaneously deenergized so that contact 55 26 is closed and the output circuit 25 of modulator PM is connected to the input circuit of amplifier MCA.

During the time that the armature of relay 27 is moving from contact 29 to contact 60 26, the picture carrier waves are interrupted. Such interruption allows the armature of relay 33 to move from contact 34 to contact 35 because of the deenergization of winding 32. This unlocks reproducing drum 12 by the 65 deenergization of relay 39. The closure of

contact 35 places a short-circuit around winding 32, so that the subsequent receipt of carrier current by demodulator RPD, upon the closure of contact 26, cannot again energize winding 32 to lock drum 12.

The varying tone values of the transparency of the picture cause varying currents through the photo-electric cell 15. Carrier waves from oscillator PO are modulated by these varying currents after amplification 75 in amplifier and PCS and transmitted to demodulator RPD. Corresponding varying currents in the output circuit of demodulator RPD causes movement of the string 31 of light valve V so that the image of the 80 aperture formed by string 31 on the light record blank on drum 12 varies in accordance with the light transmitted through the transparency of the picture at the sending drum 5.

At the conclusion of the process, switch 47 is closed to lock transmitting drum 5. The attendant at the reproducing station, observing that the movement of the light valve has ceased, can either open switch 42 or close 90 switch 38 or both to lock the reproducing drum 12.

The direction of rotation of phonic wheels 6 and 11 is now reversed. Another light sensitive record blank is placed on drum 12. 95 If a different picture is to be transmitted, a transparency of such picture is placed on sending drum 5. The same transparency is of course used if it is desired to transmit the same picture. If switch 42 only had been 100 previously opened to lock reproducing drum 12, it may now be closed and the system is in readiness to transmit another picture. If switch 38 had also been closed, it must be opened before the transmitting process can 105 begin. The process of transmitting this second picture is the same as that of the first except that the axial movement of the drums 5 and 12 is in an opposite direction.

When transmitting pictures, according to 110 the present invention, no time is lost between pictures in returning the sending and reproducing drums to starting positions. By the arrangement of this invention, the sending and reproducing drums at the finish 115 of one picture are in position for the starting of another. No complicated apparatus is required and a large saving in operating time is effected.

Various modifications of the specific embodiment of the invention which has been described may be made without departing from the scope of the invention as defined in the appended claims.

What is claimed is:

1. In a system for the transmission of pictures by electricity, optical means to scan successive elemental areas of a picture surface in a predetermined sequence for the transmission of a picture and to scan the 130

same elemental areas in reverse order to transmit a second picture, a picture drum, and means to rotate it in either of two directions and simultaneously move it axially 5 with respect to the scanning means.

2. In a system for the transmission of pictures by electricity, a picture drum, means to illuminate a small area of the surface of said drum, means to rotate said drum in 10 either of two directions and simultaneously move it axially with respect to said illuminating means, means to prevent motion of said drum in either direction, and means to disable said prevention means.
- 15 3. In a system for the transmission of pictures by electricity, a picture drum, an optical arrangement to illuminate a small area of the surface of said drum, a friction drive for rotating said drum and moving it 20 axially in either of two directions with respect to said optical arrangement, a detent to prevent rotation of said drum in either direction, and electromagnetic means for releasing said detent.
- 25 4. In a system for the transmission of pictures by electricity, sending and reproducing picture drums, means to rotate said drums synchronously and to move them axially in either direction, means to prevent 30 rotation of said drums, and means to start them synchronously in either direction.
- 35 5. In a system for transmitting pictures

by electricity, a source of carrier waves, means to modify carrier waves from said source in accordance with the elements of 35 the pictures to be successively transmitted, means including a rotatable element for reproducing the picture, and means controlled by carrier waves from said source to control the rotation of said element in either 40 direction.

6. In a system for the transmission of pictures by electricity, a circuit over which carrier waves are received, a reproducing drum, a light valve, an electron discharge 45 demodulator, means to lock said reproducing drum against motion in either direction in response to the receipt of carrier waves, means to unlock said drum due to an interruption in receipt of said carrier waves, and 50 means to prevent a subsequent locking of said reproducing drum when carrier waves are again received.

7. In an electrical system, a movable device capable of moving in either one of two 55 directions, means to cause movement of said device, a source of carrier waves, and means under the control of carrier waves from said source to effect the movement of said movable device in either direction.

In witness whereof, I hereunto subscribe my name this 29th day of April A. D. 1924.

HERBERT E. IVES.
